ATTORNEY

UNITED STATES PATENT OFFICE.

MICHAEL HOMLING, OF BUHL, IDAHO.

UNDERGARMENT.

Application filed July 12, 1922. Serial No. 574,463.

To all whom it may concern:

Be it known that I, MICHAEL HOMLING, a citizen of the United States, residing at Buhl, in the county of Twin Falls and State 5 of Idaho, have invented new and useful Improvements in Undergarments, of which the following is a specification.

This invention relates to undergarments and more particularly to combination garments, which include shirts and drawers.

An object of the present invention is to eliminate the objectionable binding at the crotch, sometimes through tightness, or insufficient length of the garment between the 15 shoulders and the crotch and yet have the garment fit sufficiently snug to be comfortable.

For this purpose, the invention aims to provide a garment which embodies an adjustable crotch strip, which may be removably and adjustably secured to the garment between the legs, so as to obtain any adjustment suitable to the wearer.

With the above and other objects in view, the invention further includes the following novel features and details of construction, to be hereinafter more fully described, illustrated in the accompanying drawings and pointed out in the appended claim.

30 In the drawings:

Figure 1 is a front elevation of a combination undergarment constructed in accordance with the invention.

Figure 2 is a rear elevation of the same.

35 Referring to the drawings in detail, wherein like characters of reference denote corresponding parts, the reference character 10 indicates the shirt or body portion of the garment, while the drawers are indicated at 11.

The garment may be made of any suitable material and of any character desired, that is, it may be of the athletic type, or may include long sleeves and legs.

In carrying out the invention, the inseam of the drawer legs is open from the crotch 45 downward for an appreciable distance and is closed by a crotch strip 12. This strip extends from the front to the rear of the garment between the legs and is adjustably held in place so as to regulate the length 50 of the garment from the shoulders to the knees, or in other words, raise or lower the crotch. For this purpose, the garment is provided both front and back with a double row of buttons 13, while the crotch strip 55 12 is provided along each side edge with button holes 14, so that the strip may be raised or lowered as desired. This provides a wide latitude of adjustment and permits the adjustment to be so made as to provide 60 additional space either at the front or rear, to suit the wearer.

The invention is susceptible of various changes in its form, proportions and minor details of construction and the right is herein reserved to make such changes as properly fall within the scope of the appended claim.

Having described the invention what is claimed is:—

70 The combination with a one piece garment, of a crotch strip extending from front to rear and between the legs of the garment, and means extending along each side edge of the strip and engageable with 75 means carried by the garment for adjustably holding the strip in position, said strip having an opening in its front, and being adjustable vertically both front and rear whereby said opening will be maintained 80 in a constant position in relation to the bottom loop of the strip.

In testimony whereof I affix my signature.

MICHAEL HOMLING.
